GAME TABLE

Isaac Ruit, Paterson, N. J., assignor of one-half
to Daniel Wagner, Paterson, N. J.

Application November 10, 1938, Serial No. 239,805

2 Claims. (Cl. 273—23)

This invention relates to that class of game tables on which balls are played, as with the aid of a cue. According to the invention, to wit, embodied in the structure of the table, and describing the same at this point only in a general way, there is a playing space which is bounded on two opposite sides by parallel rows of pockets open inwardly and at a third side is provided with a barrier; the pockets of the two rows are formed by partitions which not only converge in the direction of the barrier but are so arranged that those of either row are parallel with each other; and preferably the barrier and the partitions afford cushions to assume the impact of the balls, this cushioning being so disposed that at no point of normal play can a ball undergo a non-cushioned impact with any part of the table. The arrangement of the partitions in the particular way set forth is essential to the use of the table as the game for which it is intended and hereinafter set forth is played inasmuch as due to such arrangement and regardless of the width of the pockets the difficulty in pocketing the balls is varied, that is to say, actually graduated.

25 In the drawings,

Fig. 1 is a plan of the table, partly broken away;

Fig. 2 is a plan of one of the partitions;

Fig. 3 is a fragmentary plan of one such partition with its cover and top plate removed;

Figs. 4 and 5 are fragmentary sections on lines 4—4 and 5—5, respectively, Fig. 1;

Fig. 6 is a transverse sectional view of a partition on line 6—6, Fig. 2; and

35 Fig. 7 is a fragmentary sectional view of the barrier.

Without being limited to all the details of construction to be set forth, I describe my invention in respect to the example shown by the drawings as follows:

Let one or more longitudinal beams 1 and cross-beams 2 form with a surrounding wall 3 the frame of the table, such wall rising above the beams as shown in Fig. 5 and being here surmounted by a suitably wide strip 4. The frame is rectangular and elongated in plan. A slate slab 5 rests on the beams, being covered with felt fabric 6 and here flanked by two wood boards 7, also resting on the beams and having their top surfaces flush with that of the fabric. This slab reaches from the wall 3 at one end of the frame to near the wall at the other end, at which end there may be an elongated and suitably formed well 8 to receive the balls to be played.

55 The latter end of the table forms what I term

the "near" end, being the end from which the play starts, the other end being treated as the "far" end.

Projecting inwardly from the upstanding long sides of the wall 3 of the table are partitions 5 generally designated 10 in Fig. 1. A significant feature respecting these partitions is that the partitions of the two groups converge in the direction of the far end of the table though as to each group they are all substantially parallel with 10 each other. In the present example each group comprises the same number of partitions as the other group and each partition in either group is directly opposed to a corresponding partition in the other group. The inner ends of the partitions of either group are here parallel with the inner ends of those of the other group.

At the far end of the table there may be secured upon and across the slab 5 and boards 7, as by screws 11, a strip 12 parallel with the portion of wall 3 at the far end of the table.

In each angle formed by this strip and the corresponding side portion of wall 3 is fitted and secured, as by screws 13, a triangular element 14 whose bias margin is parallel with the 25 adjacent partition. This element extends to the same line, parallel with the long sides of the table, as do all the partitions in the corresponding group.

Adjacent said strip 12 and reaching from nearly 30 one to nearly the other of the elements 14 is a barrier element 15 which presents a convex side toward the near end of the table, being held in place by screws 16.

The partitions each have the general form in 35 plan shown by Fig. 2. Each includes a wood strip 17 having a generally rectangular cross section and having a recess 17a formed in one long side thereof. This recess and the fact that the strip is formed with a long bevel 17b at its 40 opposite side and reaching to one end of the strip provide a head 17c thereon simulating an arrow head. The surface 17d at the opposite end of the strip forms a 45° angle with the latter side which is adapted to abut squarely against one 45 of the long or side portions of the wall 3, as shown in Fig. 1.

The head of each partition is to provide a cushion at both sides thereof, wherefore a rubber strip 17x is bent around the point of the 50 head and set in a groove 19 therein, the head being then covered with felt fabric 20 which may be capped by a metal plate 21 held in place by a screw 22.

Similarly the elements 14 and 15 are to pro- 55

vide cushions, for example, as shown in Fig. 7. Here the side of the element (in the example element 15) which adjoins the playing area of the table is formed with a groove 23 in which is seated a rubber strip 24, the whole being covered with felt fabric 25.

5 The partitions are held in place as follows: Being positioned as shown in Fig. 1 and as described, a pair of parallel strips 26-27 is imposed on each group and the corresponding element 14 and secured to the table-proper (formed by the slab 5 and boards 7) by screws 28, i. e., so that each partition is held by two screws. The strips 26-27 are spaced to permit access to the 10 balls in removing them from the pockets.

15 Adjoining each partition at the near end of the table and in alignment with the corresponding strip 27 is a barrier 29 (Fig. 5) comprising a wood strip 30 having a rubber strip 31 secured to its 20 inner side, the whole being covered with felt fabric 32 and secured to the adjoining board 7 by brackets 33. The strip 31 is at the same elevation as the rubber strips of the partitions and elements 13-14.

25 The balls are indicated at *a*: The spacing of the partitions and the elevation of the strips 26-27 are of course sufficient to admit the balls *a*, which are all of the same diameter, to any pocket. Some of the pockets, as at *x*, may be wider than 30 the others. Each pocket has a depth sufficient to admit several balls.

20 The "scratch" line is indicated at 34.

There may be any number of balls, the object being for each player at his turn to play to place 35 all the balls in the pockets, using a cue. For instance, the play may be as follows:

30 All plays are made from the near end of the table, to wit, with a ball placed on the scratch line and shot toward some ball on the table, the 40 object being to pocket one or more balls on each shot. And in this connection it is noted that, since the pockets have their mouths directed away from the near end of the table, the possibility of pocketing any ball except by a caroming of either 45 the ball struck or the cue ball off some other object, as another ball or a part of the table, is very remote. Again the construction is further such that the further a pocket is removed from the barrier the greater is the difficulty, even by 50 caroming, of entering any ball into such a pocket.

55 At the outset a given ball, as a white ball, is placed on the "spot" at 35. With a ball taken from the supply in the well as a cue ball, the object is to cause the cue ball to strike the "spot" ball and pocket one or both of them (if both balls are pocketed the spot ball is returned to the spot). The same player continues using all the balls in well 8, and at each shot he may aim to strike any 60 ball on the table. When all the balls in the well have been exhausted the player's "frame" is complete and his score is determined by the sum of the values "30", "40", "50", etc., appearing adjacent the pockets in Fig. 1 containing balls.

65 The table may be regarded as providing in conformity with a single horizontal plane a playing area or "field" on its top surface between and reaching as far as the rows of partitions extend in the direction in which the partitions of the two 70 rows converge and means, as barrier 15, to check the displacement of balls appreciably from be-

tween said rows in said direction. As in the example, the barrier 15 and each partition, at least as to its inner end portion, is equipped with cushioning means; in the sense that it forms one side or wall of a pocket each element 14 may be treated as a partition.

Each pocket is elongated lengthwise of the partitions and also widened at 17a so that it may accommodate a plurality of balls. And in view of this I do not wish to be limited to the pockets 10 existing because of walls or partitions which project above the surface of the playing area, since my invention would be accomplished without that condition so long as the elongated pockets exist in two rows and with the mouths of the pockets 15 of the two rows substantially parallel, and with the longitudinal axes of the pockets of either row converging with those of the axes of the other row, and the table provides above its top surface means (as 15) to check the displacement of balls 20 appreciably from between said rows in the direction in which said axes converge.

It is known in this art (Burke Patent No. 1,964,- 378) to provide a barrier at the far end of the 25 table and rows of partitions at opposite sides of the playing area which radiate from the central portion of the barrier, the partitions increasing in length the further they are removed from the barrier. Since in such case the rows are in fact not parallel nor are the partitions of either row 30 parallel and since the balls are consequently accessible to the pockets only from a limited part of the playing area directly adjacent the barrier, such table is of course distinct not only in the 35 possibilities with respect to its use but in actual structure from my table as I herein claim the same.

Having thus fully described my invention, what I claim is:

1. In combination, structure affording a substantially plane top playing surface and having substantially parallel upstanding wall portions flanking said surface, a row of substantially parallel partitions adjacent each said wall portion and arranged on said surface, said partitions of one row converging with those of the other row in one direction in which the wall portions horizontally extend, means to secure the partitions of each row to said structure including spaced strips bridging the partitions of such row, and means upstanding above said surface and arranged to check the displacement in said direction of balls from between said rows.

2. The herein-described game table having a horizontal planiform playing area on its top surface and elongated pockets in rows opposed to each other and having said area between them and arranged with the longitudinal axes of the pockets of either row converging with the longitudinal axes of the pockets of the other row and with the mouths of the pockets of the two rows in substantially parallel lines, said table including a barrier arranged to check the displacement of balls appreciably from between said rows in the direction in which said axes converge and said barrier extending, and in plan presenting at the side thereof adjacent said area a single convex surface also extending, from substantially one of said lines to the other.
